* cited by examiner

Primary Examiner — Cathron Brooks*Assistant Examiner* — Ian Whitmore(74) *Attorney, Agent, or Firm* — Frommer Lawrence & Haug LLP; William S. Frommer(57) **CLAIM**

The ornamental design for a portion of a display screen with graphical user interface, as shown and described.

DESCRIPTION

The sole FIGURE is a front view of a portion of a display screen with graphical user interface showing my new design. The broken line showing of a display screen, mobile device, text and portions of the graphic user interface represents environmental subject matter and forms no part of the claimed design.
